US0D1107905S

(12) **United States Design Patent** (10) **Patent No.:** **US D1,107,905 S**
(45) **Date of Patent:** **** Dec. 30, 2025**

(54) **TRANSDERMAL APPLICATOR**

- (71) Applicant: **PassPort Technologies, Inc.**, San Diego, CA (US)
- (72) Inventors: **Harshal Shah**, Braintree, MA (US); **Kaitlyn Delaney Mary Leidl**, Cambridge, MA (US); **Karen Unterman**, Brookline, MA (US); **Gregg R. Draudt**, Stow, MA (US); **William J. Vespa**, Revere, MA (US); **Amy Lee Stockslager**, Cambridge, MA (US); **Hirotoshi Adachi**, San Diego, CA (US); **Uros Kascak**, San Diego, CA (US)
- (73) Assignee: **PassPort Technologies, Inc.**, San Diego, CA (US)
- (**) Term: **15 Years**
- (21) Appl. No.: **29/961,974**
- (22) Filed: **Sep. 9, 2024**

Related U.S. Application Data

CLAIM

The ornamental design for a transdermal applicator, as shown and described.

DESCRIPTION

FIG. 1 is a top perspective view of a transdermal applicator; FIG. 2 is a front view of the transdermal applicator of FIG. 1; FIG. 3 is a rear view of the transdermal applicator of FIG. 1; FIG. 4 is a right side view of the transdermal applicator of FIG. 1; FIG. 5 is a left side view of the transdermal applicator of FIG. 1; FIG. 6 is a top view of the transdermal applicator of FIG. 1; and, FIG. 7 is a bottom view of the transdermal applicator of FIG. 1.

In the drawings, the dashed broken lines represent features that form no part of the claimed design.

In the drawings, the dot-dash broken lines define the bounds of the claimed design and form no part thereof.

1 Claim, 6 Drawing Sheets

Related U.S. Application Data

a continuation of application No. 29/668,472, filed on Oct. 30, 2018, now Pat. No. Des. 965,770.
